Baldwin & Wright

UNITED STATES PATENT OFFICE

OSCAR STYLES PENN, OF MALEW, ENGLAND, ASSIGNEE TO ROADLESS TRACTION, LIMITED, OF HOUNSLOW, MIDDLESEX, ENGLAND, A COMPANY OF GREAT BRITAIN

JOINTS OF CHAIN OR LIKE MEMBERS

Application filed August 23, 1930, Serial No. 477,404, and in Great Britain September 4, 1929.

This invention relates to improvements in joints in which a number of separate links are connected to one another to form a chain, and is especially adapted for endless tracks for vehicles.

More particularly the invention is concerned with an improvement in or modification of the invention disclosed in my United States Patent No. 1,724,961 in which is described an endless track wherein the usual form of pin or metal joint is dispensed with and rubber or other resilient material is employed to give the necessary articulation of the links, the working of the joints being obtained by the flexure of the rubber which takes up the movement between adjacent links.

One prime object of the invention is to provide novel reaction blocks to remove stress due to vertical load.

Another important object is to provide a novel construction wherein the number of resilient blocks which must be employed are reduced and wherein the construction generally facilitates assembly of the parts.

Further details of the invention will be apparent from the following description and the claims appended hereto.

The invention is illustrated in the accompanying drawing, in which—

Figure 1 is a sectional elevation of one form of track, Figures 2 and 3 being respectively a transverse section on the line II—II and a plan view of Figure 1.

Referring specifically to the drawing, two types of link members are employed, one type comprising an upper part or tooth 1 and a lower part or ground plate 2. The other form of link is designated 3 and affords roller surfaces or paths. Each lower part or ground plate 2 has upstanding lugs 4 in which pin holes 5 are provided for the reception of locking pins 6 which secure the upper section or track tooth 1 to the ground plate 2. The track tooth 1 has lugs 7 interfitted with the lugs 4 and which also have pin holes for the passage of the said locking pins.

The link 3 has surfaces 8, shown in Figs. 2 and 3, and on these surfaces the rollers run which support the weight of the machine.

Intermediate these surfaces the material of the link 3 is flanged downwardly and horizontally so as to form an approximate Z section as indicated at 9 in Fig. 1.

As shown, the ground plates are preferably provided with inwardly inclined sides 10, but they may be vertical or inclined outwards. The members 2 house the main rubbers 11, through which the downward load due to the weight of the machine is transmitted from the roller surfaces or paths to the ground plates and thence to the ground. A central rubber 12 is mounted between each pair of adjacent links 3 and is held in position by a flange 13 on the underside of the track tooth 1.

There are essentially three rubbers, two main and one central rubber but each of these may be subdivided into two or more pieces. It will be appreciated that the centre or reaction rubber is relieved of all vertical load due to the weight of the machine, and that by varying its volume and vertical position, the point of flexure of the joint may be adjusted.

It will be observed that the lower parts 2 of the shoe members have substantially horizontal bottom walls and substantially vertical confining walls to support the outer blocks 11. The link members 3 have body portions resting on the outer blocks 11 and have their extremities spaced by these outer blocks from the horizontal bottom walls of the lower shoe members 2, the extremities of the link members being formed as horizontal flanges or edge portions which extend in parallel relation to the body portions and underlie the inner blocks 12. The vertical flange portions connecting the horizontal flanges to the body portions of the link members serve to separate the inner and outer blocks 12 and 11, and the flanges 13 constitute abutments on the upper shoe members between which and the horizontal flanges the inner blocks 12 are confined.

What I claim is:—

1. In an endless track, the combination of a series of link members on which roller surfaces are formed, said members being formed with downwardly extending flanges having horizontally disposed edge portions, a second

series of link members, said second link members being associated with the first link members and each comprising an upper and a lower part, said lower parts being formed
5 with upwardly extending sides, the flanges of said first link members extending down into the spaces between the upwardly extending sides of lower parts of adjacent second link members, and blocks of resilient material
10 including inner blocks and outer blocks on opposite sides of the inner blocks, all of said blocks being housed in said second link members, the outer blocks being disposed respectively between said upwardly extending sides
15 and the adjacent downwardly extending flanges to hold the first link members directly out of contact with the second link members and operatively to connect them for pivotal movement, the inner blocks being positioned
20 between and held in place by contact with said upper parts, the downwardly extending flanges of adjacent first link members, and the horizontal edges of said flanges.

2. An endless track member comprising a
25 number of separate links consisting of shoe members and link members proper, and blocks of resilient material including an inner block and outer blocks on opposite sides of the inner blocks for holding the shoe and link members out of metallic contact, the said shoe members comprising detachably secured upper and lower portions, the lower portions having horizontal bottom walls and substantially vertical confining walls to support the
30 outer blocks, said link members having body portions resting on the outer blocks and having their extremities spaced thereby from said horizontal bottom walls, said extremities being horizontal flanges, extending in parallel
35 relation to the body portions and underlying the inner blocks, vertical flange portions connecting the horizontal flanges to the body portions of the link members and separating the inner and outer blocks, abutments on the
40 upper shoe members, the inner blocks being confined between said abutments and the above mentioned horizontal flanges, and clearances between the body portions of the links and the shoe members.
45

50 In testimony that I claim the foregoing as my invention I have signed my name this 13th day of August, 1930.

OSCAR STYLES PENN.
